RECOILLESS RIFLE

C Walton Musser, Beverly, and Kenneth R. Wadleigh, Belmont, Mass., assignors to the United States of America as represented by the Secretary of the Army

Filed Nov. 26, 1958, Ser. No. 776,653

4 Claims. (Cl. 89—1.7)

The invention described herein may be manufactured and used by or for the Government for governmental purposes without the payment of any royalty thereon.

This invention relates to recoilless rifles such as are adapted to be fired from the shoulder. More particularly, it relates to a recoilless rifle which is adapted to fire a cartridge of the type wherein a propellant is interposed between a perforated casing and a perforated boom containing a powder for igniting the propellant.

In guns of this type, lightness of weight and simplicity of operation are prime considerations. The rifle of the present invention is given these advantages by a unique and radical departure from the recoilless rifles in use at the present time. In it, the conventional breech mechanism, with its difficult-to-machine kidney-shaped nozzle, is altogether eliminated, and in its place there is substituted a circular nozzle which is an integral part of the cartridge.

Another unique feature is the provision of a relatively simple firing mechanism including a sear which functions to (1) hold the firing pin away from the primer prior to the cocking of the hammer, (2) lock the hammer in its uncocked position when the gun has been fired, and (3) lock the circular nozzle to the chamber.

The invention will be better understood from the following description when considered in connection with the accompanying drawings and its scope is indicated by the appended claims.

Referring to the drawings:

Figs. 1 and 2 illustrate the general assembly of the rifle, and

Fig. 3 illustrates the various parts of the firing mechanism and cartridge.

The gun of Figs. 1 and 2 includes a barrel 10, a chamber 11, a circular nozzle 12, and a firing mechanism 13. The hammer (not shown in Fig. 1) of the mechanism 13 is cocked by a cocking lever 14. The mechanism 13 is operated to fire the gun by means of a hand trigger 15 and a cable 16. The barrel 10 supports a telescope 17 and is arranged to be supported either upon the shoulder or upon a retractable monopod 18 and the shoulder rests 19 and 20 which are adapted to be swung downwardly in the form of a bipod.

Fig. 3 illustrates, among other things, a cartridge including a perforated casing 21 and a boom 22 which bears fins 23 and is made hollow and perforated to receive a powder for igniting a propellant interposed between the boom and the casing.

At its rear end, the cartridge has a closure which includes a metal pressure plug 24, a plastic plug 25 and the nozzle 12. For firing the propellant igniting powder of the cartridge a primary 26, mounted on the nozzle 12, is connected with the interior of the boom 22 through an outlet 27 extending through the nozzle 12, the plastic plug 25 and the pressure plug 24.

The nozzle 12 is provided with three threads 28 which are adapted to engage similar threads 29 of the chamber

11 for securing the two together. These threads have a lead angle of not more than seven degrees.

Around the periphery of the nozzle 12 are three equally spaced primers and outlets similar to the primer 26 and outlet 27. These are provided so that, no matter how the round is inserted into the chamber, a primer is always in line with the firing pin 30. Plastic plug 25 and pressure plug 24 are similarly provided with a plurality of passageways or outlets which provide communication between the primer and the igniting powder of the cartridge.

In assembling the cartridge of Fig. 3, the projectile (not shown) is placed in the case 21 to its proper depth. The correct quantity of powder is then placed in the case 21 and the pressure plug 24 is screwed into the boom 22. The nozzle 12 is then placed upon the plastic plug 25 until an index hole 31 therein engages a protrusion on the plug 25. This aligns the gas passages or primer outlets of the mating parts. A gland nut 32 is then screwed into the nozzle 12 thereby locking all parts of the cartridge together so that it is ready for insertion into the gun. Once in the gun, the projectile is rotated to tighten the threads 28 and 29 and is locked in its final position by a rear extension of a sear 33 of the firing mechanism.

The firing mechanism includes, in addition to the firing pin 30, the sear 33 and the cocking lever 14, a hammer 34, a firing rack 35, a pin 36 for supporting the rear end of this rack, a cam 37 fixed to the housing of the firing mechanism, a spring 38 connected between the front ends of the rack 35 and the sear 33, a sear actuator 39, a firing cable 16, a cable housing adapter 40 and a cable housing 41.

It will be noted that the sear 33 has on one of its sides an extension 42 which functions to lock the nozzle to the chamber. On the other side of the sear are cams 43 and 44 and a notch 45.

The hammer 34 is shown by Fig. 3 as in the position which it assumes upon the introduction of the cartridge into the gun. In this position, the nozzle 12 is locked to the chamber 11 by the extension 42 of the sear, the firing pin 30 is locked away from the primer 26 by the cam 43, and the spring 38 is partially contracted.

Cocking of the hammer 34 by the exterior cocking lever 14 moves the firing rack 35 rearwardly over the cam 37 into the position indicated by broken lines where it is held by the stop 45. This also tensions the spring 38.

Firing of the gun is effected by operating the trigger 15 (see Fig. 1) to pull the firing cable forward. This produces three different results. It moves the cam 43 out of the way of the firing pin 30. It brings the cam 44 into engagement with the forward part of the firing rack 35 so that this part is raised above the catch 37 and the gun is fired. It permits the extension 42 to drop to a lower level in which the sear is prevented from returning to the position illustrated in Fig. 3. In this position, the forward part of the rack 35 is in engagement with the notch 45 and the hammer 34 is locked in its uncocked position.

As the extension 42 of the sear 33 is drawn forward it disengages from a slot in the nozzle 12. This permits the nozzle 12 to be rotated and withdrawn from the rifle. When it is withdrawn the sear 33 is returned rearwardly to the position shown in Fig. 3 by the action of spring 38. This locks the firing pin 30 in the up position and releases the rack 35 to permit cocking the rifle by cocking lever 14.

The spring 38 has a multiple function. In the fired position, the addition to repositioning the sear 33, it serves to return the cable 16 to its prefired position, thereby making certain that the ball-end of the cable in the trigger mechanism is firmly engaged with the trigger.

The spring also serves as the source of energy imparted to the hammer when it is in the cocked position.

The firing mechanism is designed so that a round, when inserted, is locked in place by the sear 33 which engages a slot cut in the locking thread of the nozzle. Once in place, it can be removed only after firing or by holding the lever 14 in the cocked position and pulling the trigger. This action permits the sear 33 to return and engage the firing pin so that the primer is not fired by releasing the cocking lever.

When the gun is fired, a high gas pressure is built up within the casing 21 since the gases are confined by the pressure plug 23. This is essential in order for the projectile to be expelled from the rifle at maximum efficiency. When the pressure within the casing 21 attains a predetermined value, the plastic 25 fractures and the pressure plug 24 travels with the projectile as a part of the boom 22.

The gases expand into the chamber 11 through the holes in the casing 21, and, after the projectile is expelled, return through the casing holes and pass out through the nozzle 12.

We claim:

1. In combination with a gun barrel, a chamber having a front end affixed to and communicating with the back end of said barrel, locking threads around a rear end of said chamber, a cartridge including a perforated casing for reception within said chamber and a projectile boom axially of said casing, a pressure plug screw-threadedly mounted to the rear portion of said boom, a pressure-sensitive frangible closure mounted about said plug, a circular nozzle disposed in contacting relation and rearwardly of said closure, said nozzle being exteriorly threaded intermediate its ends to co-operate with the locking threads of said chamber for rotating said nozzle to a predetermined position, a plurality of spaced primers disposed around the periphery of said nozzle, each of said nozzles having a passageway leading from said primers, a plurality of passageways disposed in said frangible closure, each of said frangible closure passageways being capable of registering with each of said nozzle passageways, a plurality of passageways disposed in said pressure plug, each of said pressure plug passageways being capable of registering with each of said passageways in said frangible closure, said cartridge having a propellant disposed between its perforated casing and said boom, an igniting powder within said boom for igniting said propellant and wherein one of said primers is in communicating relation with the igniting powder through a passageway in said frangible closure and pressure plug.

2. The device of claim 1 wherein a sear is supported on said chamber, said sear having at a rear portion an inwardly extending lug for engaging and locking said nozzle in said predetermined position.

3. A breechless recoilless rifle comprising a gun barrel, a chamber having a front end affixed to and communicating with the back end of said barrel, locking threads around a rear end of said chamber, a cartridge including a perforated casing for reception within said chamber and a projectile boom axially of said casing, a pressure plug screw-threadedly mounted to the rear portion of said boom, a pressure-sensitive frangible closure mounted about said plug, a circular nozzle disposed in contacting relation and rearwardly of said closure, said nozzle being exteriorly threaded intermediate its ends to co-operate with the locking threads of said chamber for rotating said nozzle to a predetermined position, a plurality of spaced primers disposed around the periphery of said nozzle, each of said nozzles having a passageway leading from said primers, a plurality of passageways disposed in said frangible closure, each of said frangible closure passageways being capable of registering with each of said nozzle passageways, a plurality of passageways disposed in said pressure plug, each of said pressure plug passageways being capable of registering with each of said passageways in said frangible closure, said cartridge having a propellant disposed between its perforated casing and said boom, an igniting powder within said boom for igniting said propellant and wherein one of said primers is in communicating relation with the igniting powder through a passageway in said frangible closure and pressure plug.

4. The device of claim 3, wherein a sear is supported on said chamber, said sear having at a rear portion an inwardly extending lug for engaging and locking said nozzle in said predetermined position.
